WINDOW SUPPORT

Alfred H. Haberstump, Detroit, Mich., assignor
to The Murray Corporation of America, a cor-
poration of Delaware

Application October 14, 1933, Serial No. 693,535

11 Claims. (Cl. 296—48)

My invention relates to window supporting means and particularly to the supporting and guiding means for a window mounted in a door of a cabriolet type of body.

5 It has been the practice heretofore in providing windows for doors of the cabriolet type, that is to say, for doors ending at the belt line of the body, to provide a frame about the glass having extensions at the lower side edges which act as 10 guides and supports when the window is in raised position. The guides operate in channels at the edges of the door and are provided with friction reducing means, such as balls and wheels, which not only permit the free operation of the frame 15 but, being biased in opposite directions, prevent the lateral and longitudinal tilting movement of the window.

In practicing my invention I make possible such 20 a support for a window in a door of the above mentioned type which is disposed in the vicinity of the wheel housing. In view of the presence of the wheel housing in the body, the rear lower portion of the door must be cut away, as is well known in the art, and for this reason the downwardly extending legs on the rear portion of the window can no longer operate at the rear door edge. To overcome this difficulty I have offset 25 the support at the rear edge of the window inwardly thereof sufficiently to clear the cutaway portion of the door. I have extended the glass guide channel of the door inwardly the same amount to provide surfaces upon which the rollers of the support may operate. As a further extension of the invention, I flange the ends of 30 at least one, if not both, of the channels and provide a set of rollers which operate on the flanges and are diametrically disposed so as to eliminate the tilting in the plane of the glass which would otherwise occur or which would 35 occur when such rollers are mounted in offset diametrical relation to each other.

Accordingly, the main objects of my invention are: to provide an offset support on the frame of a window glass which operates in an extended 40 channel to permit the support to clear a cutaway portion in the door; to provide a channel with extended sides which encompasses one end portion of the glass to provide a surface upon which offset supporting elements of the glass frame 45 may be guided; to provide flanges on the edges of the channel on which guiding rollers may be retained in biased contact to prevent a tilting movement in the plane of said window glass; to construct an offset support for a window glass 50 such that the means provided to prevent the tilt-

ing of the glass in its plane will be oppositely disposed relative to each other; and, in general, to provide a support for a glass at the cutaway portion of a door which is simple in construction, economical of manufacture and positive in 5 operation.

Other objects and features of novelty of my invention will be either specifically pointed out or will become apparent when referring, for a better understanding of my invention, to the following 10 description taken in conjunction with the accompanying drawings, wherein:

Figure 1 is a broken view, partly in section and partly in elevation, of a door and window embodying features of my invention.

Fig. 2 is an enlarged sectional view of the structure illustrated in Fig. 1, taken on the line 15 2—2 thereof.

Fig. 3 is an enlarged sectional view of the structure illustrated in Fig. 1, taken on the line 20 3—3 thereof.

Fig. 4 is an enlarged sectional view of the structure illustrated in Fig. 1, taken on the line 4—4 thereof.

Fig. 5 is a broken sectional view of structure, 25 similar to that illustrated in Fig. 1, embodying further novelty of my invention.

Fig. 6 is an enlarged sectional view of the structure illustrated in Fig. 5, taken on the line 6—6 30 thereof, and

Fig. 7 is an enlarged sectional view of the structure illustrated in Fig. 6, taken on the line 7—7 thereof.

I have illustrated in Fig. 1, a door 10 for a cabriolet type of body which is to be employed adjacent to the wheel housing of the body in such manner as to require the lower right hand corner of the door to be cut away, as at 11, to mate with the wheel housing portion of the body. A window 12 is disposed between the inner and outer 40 panel of the door in the conventional manner, having a frame 13 thereabout for providing a finish to the glass and engagement for an actuating mechanism 14 by which the glass is moved to predetermined positions.

Arms 15 on the regulator 14 are secured to a projecting plate 16 attached to the lower portion of the frame 13, having a slot 17 therein in which the headed pins 18 on the ends of the arms 15 slide. In this construction, I preferably provide 50 a slot 19 at the rear end of the plate 16 in which the pin 18 of the rearmost arms 15 may be disposed while the pin 18 on the frontwardly disposed arm is preferably secured thereon during assembly to eliminate an additional slot in the 55

plate 16 at which the pin 18 on the rearmost arm 15 could pass during the operation of the window.

The main novelty of my invention resides in the method of supporting the window in the door 5 against lateral and longitudinal tilting movements during the time it is moved or after it is disposed in predetermined position. In Figs. 1, 2 and 3, I have shown a method of supporting the front edge of the window frame by the channel element 10 21 provided as an extension of the front frame edge which is interconnected with the plate 16 by the cross brace 22 to add strength to the assembly. A roller 23 and bell crank arms 25 disposed on either side thereof are mounted on a fixed pivot 15 24 within the channel element 21.

On one arm of the bell crank a roller 26 is pivoted to be biased outwardly, away from the channel element 21, by a spring 27 mounted in engagement with the opposite arms of the bell 20 crank. In this manner, lateral pressure is provided by the rollers 23 and 26 to retain them in engagement with the sides of a glass run channel 28, provided on the left hand face of the door jamb. When two pairs of such rollers are employed, as illustrated more clearly in Figs. 1 and 2, 25 any tilting movement laterally of the plane of the glass is prevented and the window may readily be operated.

A more serious problem obtains when 30 constructing a similar guide and bracing means on the rear edge of the window above and adjacent to the cutaway portion 11 of the door which mates with the wheel housing of the body. Referring more particularly to Figs. 1 and 4, I have 35 illustrated a bracing construction which is new and novel. A channel element 29 is mounted on the rear door jamb having elongated sides 31 which project outwardly such an extent that the outer edges are disposed opposite to the cutaway portion 11 to be available to act as guides for an 40 offset extension on the frame which will now be described.

Inwardly from the rear lower corner of the frame 13 a channel-shaped element 32 is provided, as illustrated more clearly in Fig. 4, mounted 45 intermediate the side edges of the frame 13 inwardly from the rear frame edge. The element 32 is braced by a triangular shaped element 33 which may be a casting, an extruding metal portion 50 or any suitable type of gusset plate, for strengthening the channel and retaining it in predetermined position. The channel 32 is provided with a double set of rollers 23 and 26 which are similar to those illustrated and described more 55 particularly with reference to Fig. 2 and which function in the same manner relative to the sides 31, as described above relative to the sides of the channel 28 disposed on the left hand side of the door. In this manner, both the front and 60 rear edges of the door are supported against a movement laterally of the plane of the window in any of its positions. A strip of felt rubber or like material 30 may be provided on the web of the channels 28 and 29 to prevent the longitudinal 65 tilting of the window.

A further extension of my invention, I have 70 illustrated in Figs. 5, 6 and 7, the disposition of roller elements in aligned relation to each other which prevent a tilting movement of the window longitudinally of its plane of movement. The channel on the left hand edge of the window, that is to say, the edge opposite to that having the 75 cutaway portion 11, is provided with a channel 35 which is similar to the channel 28 with the exception that the outer edges are flanged out-

wardly at 36 to be employed as tracks with which a pair of rollers 38 contact.

The rollers 38 are mounted on a pair of arms 39, as illustrated more clearly in Fig. 7, which extend outwardly from a cup portion 41 in which a spring 42 is retained by a bolt 43 which extends through the web of the channel 21. The tension of the spring 42 is adjusted by a nut 40 provided on the threaded end of the bolt 43. The cut 41 has an extending portion 44 provided with arms 45 10 which engage notches 46 in the edges of the sides of the channel element 21. In this manner the rollers 38 are retained in cantilever suspension which maintains the rollers against movement relative to the tracks 36. The loading of the 15 rollers may be regulated by the adjustment of the nut 40, which will remain constant in view of the fixed position of the arms 44 relative to the channel element 21.

The channel 41 with the elongated sides provided at the rear portion of the door having the cutaway portion 11, is likewise provided with the outwardly extending flanges 36 upon which a pair of rollers 38 are mounted in the same manner as the rollers 38, above described, are mounted 25 relative to the channel 35.

The pairs of rollers 38 are oppositely disposed so as to prevent the tilting of the window in its plane of movement. The pairs of rollers 23 and 26, above described, are mounted on either side 30 of the pairs of rollers 38 to prevent the lateral tilting movement of the window. In this construction, the window is retained rigid against movement either laterally or longitudinally of its 35 plane of movement in spite of the fact that the lower right hand corner of the door is cut away to mate with the wheel housing, which prevents a supporting arm at its edge from extending downwardly within the door when the window is lowered.

While I have described and illustrated but a single embodiment of my invention, it will be apparent to those skilled in the art that various changes, omissions, additions and substitutions may be made therein without departing from the 45 spirit and scope of my invention, as set forth in the accompanying claims.

I claim as my invention:

1. A door for a vehicle body having the lower corner thereof cut away, a window glass, a glass-guide channel mounted within the inner confines of the door having less depth at the cut-away corner and having an outer edge substantially parallel to the path of movement of the window glass.

2. A door for a vehicle body having the lower corner thereof cut away, a window glass, a glass-guide channel mounted within the inner confines of the door having less depth at the cut-away corner and having an outer edge substantially 55 parallel to the path of movement of the window glass and an offset supporting arm on the lower edge of the window glass within the confines of the extending sides of said channel.

3. A door for a vehicle body having the lower corner thereof cut away, a window glass, a channel disposed within the confines of said door, having less depth at the cut-away corner and having an outer edge substantially parallel to the path of movement of the window glass, a 70 downwardly projecting supporting arm mounted on the window glass, rollers provided on said arm in engagement with the sides of said channel to prevent the tilting of the window laterally of its plane.

4. A door for a vehicle body having one lower corner thereof cut away, a window glass, a channel provided within the confines of said door and adjacent to the cut-away portion having less depth at the cut-away corner and having an outer edge substantially parallel to the path of movement of the window glass, a support on the lower edge of said window glass aligned with the outer edges of said channel, a channel of shallow depth provided on the opposite side of said door, a support on the window glass adjacent to its edge and disposed within said last channel, and rollers on both of said supports in engagement with the sides of said channels to prevent the tipping of the window glass laterally of its plane of movement. 5
5. A door for a vehicle body, a window for said door supported to be moved upwardly and downwardly therein, a guide projecting below and in continuation of one edge of said window, a second guide projecting below and in the plane of said window inwardly of the other edge of said window, and channels provided in said door having sides of such extent as to encompass said window guides. 10
6. A door for a vehicle body, a window for said door supported to be moved upwardly and downwardly therein, a guide projecting below and in continuation of one edge of said window, a second guide projecting below and in the plane of said window inwardly of the other edge of said window, channels provided in said door having sides of such extent as to encompass said guides, and rollers provided on said guides in engagement with the sides of said channels for supporting said window against a tilting movement laterally of its plane. 15
7. A door for a vehicle body, a window for said door supported to be moved upwardly and downwardly therein, a guide on one end of said window at the edge thereof, a second guide for said window mounted intermediate of the window edges, channels provided in said door having sides of such extent as to encompass said guides, 20 rollers provided on said guides in engagement with the sides of said channels for supporting said window against a tilting movement laterally of its plane. 25
8. A door for a vehicle body having channels at its side edges for encompassing the edges of the window glass, outwardly projecting flanges at the edges of the channels, and rollers carried by said window in engagement with said flanges to prevent the tilting movement of the window longitudinally of its plane of movement. 30
9. A door for a vehicle body having channels at its side edges for encompassing the edges of the window glass, outwardly projecting flanges at the edges of the channels, rollers carried by said window in engagement with said flanges to prevent the tilting movement of the window longitudinally of its plane of movement, and rollers projecting laterally of the window in engagement with the sides of said channels to prevent the tilting movement of the window laterally of its plane of movement. 35
10. A door for a vehicle body having at least one lower corner cut away, a channel mounted at the cut-away side of the door having extended sides such that the outer edges are disposed opposite to said cut-away portion, a window in said door disposed between the sides of said channel, a projection on said window inwardly of its edge within the confines of said channel side, and rollers provided on said projection engageable with the sides and ends of said channel to prevent the tilting movement of the window laterally and longitudinally of its plane of movement. 40
11. A door for a vehicle body having channels at its side edges for encompassing the edges of the window glass, outwardly projecting flanges at the edges of the channels, and means carried by said window glass in engagement with said flanges to prevent the tilting movement of the window longitudinally of its plane of movement. 45

ALFRED H. HABERSTUMP. 45
